UNITED STATES PATENT OFFICE.

ANTONIO VINCENT, OF OAKLAND, CALIFORNIA.

TRIP-HAMMER.

1,342,782.

Specification of Letters Patent.

Patented June 8, 1920.

Application filed June 4, 1919. Serial No. 301,731.

To all whom it may concern:

Be it known that I, ANTONIO VINCENT, a citizen of the United States, residing at Oakland, in the county of Alameda and State 5 of California, have invented certain new and useful Improvements in Trip-Hammers, of which the following is a specification.

My invention is a trip hammer particularly useful for beating gold into leaf form, 10 and is an improvement over my trip hammer disclosed in my Patent No. 1,297,940, dated March 18, 1919.

My improved trip hammer is constructed and arranged to strike a light blow and a 15 heavy blow, the light blow being employed at first for beating the mass of gold out thin and the heavy blow being thereafter employed to beat out the thin gold into leaf form.

20 My invention is illustrated in the accompanying drawings which form a part of this specification.

Referring to the drawings:

Figure 1 is a side elevation of my invention.

Fig. 2 is a transverse section thereof taken on line 2—2 of Fig. 1.

Fig. 3 is a plan view of the double interchangeable cam.

30 Fig. 4 is an end view of the double interchangeable cam.

Fig. 5 is an end view of the smaller of said double interchangeable cam.

Fig. 6 is an end view of the larger of 35 said double interchangeable cam.

Fig. 7 is a sectional view on line 7—7 of Fig. 2 showing the cam operating connections.

Fig. 8 is a sectional view of the clutch.

40 In the drawings 1 indicates a frame on which are bearings 2 in which are journaled a shaft 3. On one end of said shaft is secured a worm gear 4 and on the other end of said shaft is secured a fly wheel 5.

45 The worm gear 4 meshes with a worm 6 on shaft 7 journaled at one end in a bearing 8 on the frame 1, and at its other end in a bearing 9 mounted on a platform 10 secured at one end to said frame. A shaft

50 12 is arranged to be clutched to shaft 7 by a friction clutch 13, one member 14 of said clutch being journaled in bearing 9 by means of its journal 15 and keyed on the end of shaft 12 and the other clutch member 16

55 keyed on shaft 7. The end of shaft 7 extends into and is journaled in the journal

15 of clutch member 14. The clutch member 16 is formed with an annular groove 18 which is engaged by one arm of a clutch operating lever 19 pivoted to the platform 60 10 to which is connected suitable operating means 19'. A collar 20 is secured by set screw 21 to the outer end of the clutch journal 15 to prevent the journal 15 from sliding in the bearing 9 in one direction. 65

On the shaft 3, between the bearings 2, are mounted two double interchangeable cams 21, each of which comprises a smaller cam 22 and a larger cam 23, the cams 22 being fixedly keyed to shaft 3 and the cams 70 23 being slidably keyed on said shaft by means of key 24 and key notches 25 and 26 in said cams 22 and 23. The cams 23 are formed with recesses 27 to receive the cams 22 so that the cams 23 may slide over the 75 cams 22 as shown in Figs. 3 and 4. The cams 22 have notches 28 in the periphery of their hubs into which project lugs 29 on the hubs of cams 23 which serve in addition to key 24 to prevent relative turning of the 80 cams 22 and 23. The hub of each cam 23 is formed with an annular groove 30 each of which is engaged by an arm of a lever 31 pivoted at 32 on the frame 1. Links 33 are connected at one end to lever 31 and their 85 other end to arms 34 secured to a rock shaft 35 by a set screw 36, said rock shaft being journaled in frame 1. A treadle 37 is secured to rock shaft 35 which when depressed, the cams 23 are shifted over the cams 22, 90 through the medium of rock shaft 35, arms 34, links 33 and levers 31.

A bracket 40 is secured to frame 1 between the cams 21, to the upper end of which a rod 41 is pivoted by pivot 42. An actuator 95 43, including side members 44 and a lower cross member 45 is slidably mounted on rod 41 extending through said cross member in sliding engagement therewith, and is connected at its upper end to the lower elbows 100 of swinging yokes 46, by means of pivots 47 extending through the upper ends of side members 44 and said lower elbows of yokes 46, which yokes are fulcrumed in a bracket 48 on the top of frame 1 by means of a bolt 105 49. The upper end of rod 41 extends through a cross head 50 slidably mounted on the actuator 43 on the side members 44 thereof, and a nut 51 screws on the upper end of said rod against said cross head. A 110 seat 52 is formed on the lower portion of rod 41 upon which the actuator 43 normally

rests. A spring 53 surrounds rod 41 and bears at its ends against cross member 45 and cross head 50, holding the cross head against nut 51. By turning said nut the 5 cross head is moved along actuator side members 44 to compress or to allow the spring 53 to expand, thus adjusting the tension of the spring. A swinging hammer 55 comprises a head 56 and a lever arm 57 10 which carries the head on its forward end and extends between the yokes 46 and is fulcrumed at its rear end in bracket 48 by bolt 49. The lever arm 57 may be made in two sections 58 and 59, joined together by a 15 suitable joint 60, the section 58 being of metal and fulcrumed by bolt 49 in bracket 48 and the section 59 being of wood and carrying the head 56. Two arms 61 extend respectively from the sides of the hammer lever member 58 between the lower and upper arms 62 and 63 of the yokes 46. Rods 64 extend through the arms 61 respectively, through the yoke arms 62 and 63 of the yokes 46 respectively, and through the bars 20 65 and 66 which tie the yoke arms 62 and the yoke arms 63 respectively together and give rigidity to said yokes. Nuts 68 and 69 screw on the lower and upper ends of rods 64 against the tie bars 65 and 66, holding 25 said bars and said rods in position. Cup-shaped collars 70 and 71 surround the rods 64 between the arms 61 and yoke arms 62 and similar collars 72 and 73 surround said rods between the arms 61 and yoke arms 63. 30 Nuts 74 and 75 screw on the rods 64 between the yoke arms 62 and collars 70, the nut 74 screwing against said yoke arm and nut 75 determining the position of collars 70 on said rods. Nuts 76 and 77 screw on the rods 35 74 between the yoke arms 63 and collars 73, the nut 76 screwing against the arms 63 and the nut 77 determining the position of collars 73 on said rods. Springs 80 surround the rods 64 and bear at their ends against 40 collars 70 and 71, forcing said collars against nuts 75 and arms 61 respectively. Springs 81 surround rods 64 and bear at their ends against collars 72 and 73, forcing said collars against arms 61 and nuts 77 respectively. 45 50 An anvil 90 rests directly beneath the hammer head 56, on which the gold is placed to be beaten.

The operation of my invention is as follows: The gold to be beaten is placed within 55 the leaves of a parchment and the parchment and gold therein are placed upon the anvil 90, as shown in Fig. 1. The clutch 13 is thrown into operation and the power is applied by the motor 11, through the medium 60 of shaft 12, coupling 17, clutch 13, shaft 7, worm 6 and worm gear 4 to shaft 3 so that the shaft rotates counter-clockwise. During 65 each revolution of shaft 3 the cams 21 engage the actuator cross member 45 and lift the actuator 43 on rod 41 against the ten-

sion of spring 53, said spring being compressed between said cross member and cross head 50. The upward movement of said actuator swings the yokes 46 upwardly on their fulcrum 49, and the yokes, through the 70 medium of springs 80, nuts 75, collars 70 and 71 and arms 61, swing the hammer 55 upwardly on its fulcrum 49, until the cams 22 escape the actuator cross member 45, whereupon the actuator slides down on the rod 75 41, and the yokes 46 swing down on their fulcrum 49 by gravity and under the influence of spring 53, and the hammer swings down by gravity and under the influence of springs 53 and 81 through the medium of 80 actuator 43, yokes 46, nuts 77, collars 73 and 72 and arms 61. When the hammer thus swings down its head 56 strikes the parchment on the anvil a light blow. The hammer is thus operated with cams 22 to strike the 85 parchment light blows until the gold in the parchment is beaten out rather thin. The larger cams 23 are then shifted over the 90 cams 22 under the actuator cross member 45 through the medium of treadle 37, upon depressing the same, rock shaft 35, arms 34, links 33 and levers 31, and the larger cams 23 engaging said actuator cross member cause the hammer through the medium of 95 the actuator 43, yokes 46 and spring connections described to strike the parchment heavy blows and beat the gold out into leaf form.

The springs 81, 80 and 53 absorb the shocks of the hammer due to the impact 100 thereof or to the vibration of the machine, and causes the hammer to strike the parchment with uniform blows of the desired power, whereby the gold in the parchment is beaten uniformly and evenly in leaf form. 105

When the pedal 37 is released springs 32', which are connected to lever 31 and frame 1, shift said cams off the cams 21 and from under actuator cross member 45, and normally maintain the cams 22 out of operation 110 and allow cams 21 to operate.

Having described my invention, I claim:

1. A trip hammer including a hammer, actuating means for said hammer, two cams for respectively engaging said actuating 115 means to cause said hammer to strike a light blow or a heavy blow, means whereby one of said cams is shifted over the other cam for engaging said actuating means, and shifted off said other cam to enable said 120 other cam to engage said actuating means, and means for operating said cams.

2. A trip hammer including a hammer, actuating means for said hammer, a shaft, two cams mounted on said shaft for respectively engaging said actuating means, to cause said hammer to strike a light blow or a heavy blow, one of said cams being slidably keyed on said shaft to slide over the other cam to engage said actuating means 130

- or to slide off said other cam to enable said other cam to engage said actuating means, means for shifting said slidale cam as aforesaid and means for rotating said 5 shaft.
3. A trip hammer including a hammer, actuating means for said hammer, a shaft, a cam fixed to said shaft for engaging said actuating means to cause said hammer to strike a light blow, a second cam slidably keyed on said shaft for engaging said actuating means to cause said hammer to strike a heavy blow, means for shifting said second cam over said first cam to cause said second 10 cam to engage said actuating means for shifting said second cam off said first cam to enable said first cam to engage said actuating means, and means for rotating said shaft.
- 20 4. A trip hammer including a hammer, actuating means for said hammer, two cams for respectively engaging said actuating means to cause said hammer to strike a light blow or a heavy blow, pedal operated means for shifting one of said cams over the other cam to cause it to engage said actuating means, means for shifting said cam off said other cam to enable said other cam to engage said actuating means, and means for operating 25 said cams.
5. A trip hammer including a hammer, actuating means for said hammer, two cams for respectively engaging said actuating means for causing said hammer to strike a light blow or a heavy blow, means for shifting one of said cams over the other cam to cause it to engage said actuating means, means for shifting said cam off said other cam to enable said other cam to engage 30 said actuating means, and means for operating said cams.
6. A trip hammer including a hammer, actuating means for said hammer, two cams for respectively engaging said actuating means to cause said hammer to strike a light blow or a heavy blow, a shifting lever engaging one of said cams, a rock shaft, an arm on said rock shaft, a link connecting said shifting lever and said arm, a pedal on said shaft for rocking said shaft to shift 45 the cam engaged by said lever over the other cam to cause said shifted cam to engage said actuating means, a spring for normally holding said shiftable cam off said other cam and out of engagement with said 50 actuating means, and means for operating said cams.
7. A trip hammer including a hammer, actuating means for said hammer, two double interchangeable cams, means to enable one cam or the other cam of each double cam to engage said actuating means to cause said hammer to strike a light blow or a heavy blow, and means for operating 55 said cams.
8. A trip hammer including a hammer, actuating means for said hammer, two cams for respectively engaging said actuating means to cause said hammer to strike a light blow or a heavy blow, means for shifting one of said cams over the other cam to enable said cam to engage said actuating means, or for shifting said cam off said other cam to enable said other cam to engage said actuating means, one of said cams 65 having a notch therein, a lug on the other cam for engaging said notch when one of said cams is shifted over the other cam, and means for operating said cams.

In testimony whereof I affix my signature. 80

ANTONIO VINCENT.
